WILLIAM H. STEDMAN, OF HARTFORD, CONNECTICUT, ASSIGNEE TO THE
MERROW MACHINE COMPANY, OF HARTFORD, CONNECTICUT, A COR-
PORATION OF CONNECTICUT.

TRIMMING MECHANISM FOR SEWING-MACHINES.

No. 798,633

Specification of Letters Patent.

Patented Sept. 5, 1905.

Application filed October 7, 1903. Serial No. 176,145.

To all whom it may concern:

Be it known that I, WILLIAM H. STEDMAN, a citizen of the United States, residing in the city of Hartford, county of Hartford, and State of Connecticut, have invented certain new and useful Improvements in Trimming Mechanism for Sewing-Machines; and I do hereby declare the following to be a full, clear, and exact description of the same, reference being had to the accompanying drawings, forming a part of this specification, and to the figures of reference marked thereon.

The improvements are particularly, though not exclusively, designed for use in trimming mechanism of the general character shown and described in the Patent No. 733,760, issued to me July 14, 1903, such trimming mechanism embodying a vibrating and a relatively fixed cutter for trimming the fabric.

The invention relates to the supporting, adjusting, and securing of the knives or cutters; and its object is to improve the general construction and operation of these portions of the trimming mechanism.

In the drawings, Figure 1 is a front elevation of a trimming mechanism embodying the present improvements with adjacent parts of an overseaming-machine in dotted lines. Fig. 2 illustrates the same parts in end elevation.

Fig. 3 is an elevation of the stationary cutter, its holder or carriage, and the support for the latter, looking at the side opposite that seen in Fig. 2. Fig. 4 is a view, principally in vertical section, taken on the line 4-4, Fig. 1.

Fig. 5 is a view, principally in horizontal section, taken on the line 5-5, Fig. 1. Fig. 6 is a vertical sectional view showing the means whereby the stationary cutter is secured to its holder. Fig. 7 is an end elevation of the holder or carriage for the lower or stationary cutter.

Like numerals of reference in the several figures indicate the same parts.

The number 22 denotes the vibrating cutter, and 23 the coöperating relatively fixed cutter. In connection with the cutter 22 a lever or carrier 24 is provided, usually pivoted at its rear end on the pin 26 and supported near its opposite or forward end by a block 27, encircling an eccentric 14, slidably located in the carrier, so that the rotation of the eccentric imparts vibratory motion to the carrier 24 and the cutter 22. The carrier 24 has a lat-

erally-extending arm 24^a, on which a carriage 29 is mounted and held by a dovetail connection, the said cutter being adjustably secured to the carriage, as heretofore. The carriage 29 is itself retained against accidental lateral displacement on the arm by a clamping-plate 27, secured to the said carriage by a screw 28 and adapted to bind upon the carrier-arm.

Describing now the improvements as embodied in the devices shown in the drawings, the number 33 denotes a standard supporting the fixed cutter 23, the latter being secured to a holder or carriage 34, adjustably mounted on the standard. The adjustment of the holder or carriage is effected by a screw 35 in the standard and having a flange 35^a entering a notch in the said holder or carriage. To secure the holder 34 in an adjusted position, the rear side of the standard 33 is cut out to receive a clamp 36, Fig. 4, whose opposite ends respectively engage the standard and holder. Approximately midway its length the clamp has threaded connection with a screw or bolt 38, journaled in the standard and operating to draw the clamp into or release it from binding contact with the said standard and holder.

The holder 34 is grooved on one of its faces, as at 34^a, Fig. 3, to receive the cutter 23 and has also a passage 39 intersecting the groove. This passage 39 at its end adjacent the groove 34^a opens out into a recess 39^a channeled across the face of said holder, and at its opposite end it is counterbored, as at 39^b. A cutter-clamp 40 of bolt form is mounted in the passage 39 and provided with a head 40^a, held in the recess or channel 39^a, so as to be non-rotatable, while the opposite end of the clamp or bolt is threaded and provided with a covered nut 40^b, seating in the counterbore 39^b. The bolt-head 40^a of the clamp has an undercut slot or groove 40^c crossing the same and adapted for the reception of the cutter, the wings of the slot engaging or being located adjacent either side of the cutter, as shown in Fig. 3. Upon rotating the nut 40^b to draw the bolt 40 inward the cutter 23 is clamped between the overhanging wings or walls of the undercut slot 40^c and the wall of the groove 34^a, thereby clamping the cutter firmly in position. The clamping-bolt 40 being non-rotatable in the holder, the undercut slot 40^c in the said holder remains in proper

position to receive a cutter 23 even after the removal of the latter from the holder. To prevent the cutter 23 from being bowed or sprung when the clamp is tightened, the bolt-head 40^a has lips 40^d, Fig. 6, which form continuations of the overhanging walls of the undercut slot and overlap the holder on opposite sides of the said recess or channel, thus limiting the inward travel of the bolt and providing clamping-surfaces on the bolt-head directly opposed to the bottom wall of the groove 34^c.

The point of manipulation of the clamping means for the stationary cutter being somewhat remote from the cutter itself is readily reached and being removed from other adjustments of the trimming mechanism is operated without confusion with them.

Having thus described my invention, I claim—

1. In a trimming mechanism for sewing-machines, a cutter-holder provided with a channel extending entirely across one of its faces, an adjustable cutter-clamp having a head 25 extending transversely of said channel, the clamp having a slot across its head and a groove on either side of said slot forming a channel alining with the channel in the holder and two wings for holding and clamping a cutter 30 loosely fitted between the wings and means for adjusting the said clamp to draw the cutter against the face of the holder whereby the cutter is clamped between the said wings and the said face of the holder adjacent to the 35 channel across the said holder; substantially as shown and described.

2. In a trimming mechanism for sewing-machines, a cutter, a cutter-holder provided with a cutter-clamp channel in one of its faces, 40 an adjustable cutter-clamp having a head fit-

ted in said channel and clamping portions overlying the clamping-surface of the holder on opposite sides of the channel, between which clamping portions and the holder the cutter may be clamped and means for adjusting the clamp, substantially as shown and described.

3. In a trimming mechanism for sewing-machines, a cutter-holder provided with a channel in one of its faces, a cutter-clamp having a head adjustably fitted in said channel, the clamp having an undercut groove across its head forming two wings for holding and clamping a cutter loosely fitted between the wings, the said wings having extensions or lips overlying the clamping-surface of the holder to limit the adjustment of the clamp and provide clamping portions between which and the holder the cutter may be secured and means for adjusting the clamp to draw the cutter against the face of the holder whereby the cutter is clamped between the said lips and the said face of the holder adjacent to and on opposite sides of the said channel across the holder, combined and operating; substantially as shown and described.

4. In a trimming mechanism for sewing-machines, a cutter-holder having two intersecting channels extending entirely across its face at an angle to each other and one being of greater depth than the other, a cutter located in the shallower one of said channels and an adjustable cutter-clamp having a head fitting in the deeper channel and having projections embracing both edges of the cutter to clamp the same in its channel; substantially as described.

WILLIAM H. STEDMAN.
